(57) **CLAIM**

(21) Appl. No.: **29/231,310**

The ornamental design for a combined LCD clock, thermometer, hydrometer, barometer and weather station, as shown and described.

(22) Filed: **Jun. 3, 2005**

DESCRIPTION

(51) LOC (8) Cl. **10-04**

FIG. 1 is a perspective view of a combined LCD clock, thermometer, hydrometer, barometer and weather station showing my new design;

(52) U.S. Cl. **D10/62**

FIG. 2 is a front view thereof;

(58) Field of Classification Search D10/62,

FIG. 3 is a rear view thereof;

D10/49-50; 368/10, 73; 73/170.16; 340/601;

FIG. 4 is a left side view thereof;

702/3

FIG. 5 is a right side view thereof;

See application file for complete search history.

FIG. 6 is a top view thereof; and,

(56) **References Cited**

FIG. 7 is a bottom view thereof.
